Application July 27, 1948, Serial No. 40,862

9 Claims. (Cl. 263—6)

1

The present invention relates to furnace mechanism intended for translation and lifting of work units, especially in pit furnaces such as salt baths.

A purpose of the invention is to economize on furnace space, and on equipment space generally, both horizontal floor space and head room, in mechanized furnaces, especially salt baths.

A further purpose is to simplify and cheapen the mechanism required to transfer work from one furnace to another.

A further purpose is to permit advance of work units at two different rates, one of which may be relatively rapid and the other relatively slow.

A further purpose is to aid in returning work units to an initial position after they have completed the cycle.

A further purpose is to support work units on rails extending along the top of a furnace or line of furnaces, to push the work units forward along the rails by pusher bars, to raise selected work units, for example at obstructions or at a point where a different rate of advance is required, by an elevator preferably acting on the work units at either side of the rails, and to transfer the work units in an elevated position suitably along the elevator, from the elevator to a return conveyor or from the return conveyor to the elevator by pusher bars acting in the elevated position.

A further purpose is to employ different rates of advance on pusher bars operating at different levels, and to move work units from one level to another to secure advance at the desired rate.

A further purpose is to employ lifting bars on the elevator which are discontinuous, and preferably to add temporary lifting bars in gaps, where the lifting bars are normally discontinuous.

Further purposes appear in the specification and in the claims.

In the drawings I have chosen to illustrate a few only of the embodiments in which my invention may appear, choosing the forms shown from the standpoints of convenience in illustration, satisfactory operation and clear demonstration of the principles involved.

Figures 1 to 5 are diagrams illustrating steps in the procedure which is followed.

Figure 6 is a side elevation of a furnace mechanism embodying the invention.

Figure 7 is a top plan of Figure 6.

Figure 8 is a front end elevation of Figure 6.

Figure 9 is a sectional perspective of the mechanism of Figures 6 to 8.

Figure 10 is a fragmentary perspective illustrating the elevator in raised position and a pusher bar acting on work units in such position.

2

Figure 11 is a fragmentary sectional perspective of a rail and one of the lower pusher bars.

Figures 12 and 13 are sections of Figure 11 on the lines 12—12 and 13—13 respectively.

Figure 14 is a perspective of one of the elevators, showing the insertion of a supplemental lifter bar.

Figure 15 is a circuit diagram.

In the drawings like numerals refer to like parts.

Described in illustration, but not in limitation, and referring to the drawings:

Pit furnaces have been extensively employed for heating of metals and the like, and in recent years have been very widely employed in the form of electrically heated salt bath furnaces, especially of the Hultgren type. The problem of advancing the work units automatically in such furnaces is, however, relatively difficult, as they do not lend themselves conveniently to roller hearths and other conventional furnace conveyors.

In efforts to solve this problem, comparatively complicated and space-consuming mechanism has been employed, and such equipment has particularly been wasteful of furnace space.

The present invention is concerned primarily with the automatic manipulation of work in pit furnaces, such as electrically heated salt bath furnaces, particularly with a view to obtaining greater simplicity, lower installation cost and maintenance cost, more economy of operation and greater production per unit of furnace space.

In accordance with the present invention, work units are raised and lowered vertically and are acted on by pusher mechanism in both the upper and lower positions, suitably acting at different rates.

The general nature of the invention will be understood by reference to Figures 1 to 5. Considering Figure 1, rails 30 extend suitably horizontally, conveniently at the top of a furnace or line of furnaces 31, conveniently located immediately below the space between the rails, and desirably of pit type, so that work can be inserted downwardly into the same.

Supported on the rails are work units 32, suitably extending from rail to rail and depending into the space or spaces of the furnace or furnaces, as later explained.

When work units are referred to herein it will be understood, as well known in the art, that these units include work holders, fixtures and work held thereon, although it will be understood that in certain cases the shape of the work may be sufficiently advantageous that it is possible to

eliminate the fixtures or the fixtures and the holders, so that in an exceptional case the work unit might consist wholly of the work. For example, a T-shaped weldment of suitable size might be handled in this manner.

Cooperating with and suitably within the rails as later explained, are pusher bars 33 having dogs to be described, and capable of reciprocation by mechanism later referred to. The pusher bars 33 are in the forward position in Figure 1 and have just advanced a group of comparatively closely spaced work units 32' along the rails at an intermediate point between the beginning and end of the furnace or line of furnaces. Behind this relatively closely spaced group 32' is a comparatively widely spaced group of work units 32², and in advance of the closely spaced group of work units 32' is a comparatively widely spaced work unit 32³.

An elevator 34 is conveniently located at either side of the rails, extending longitudinally thereof, and having lifter bars 35 adapted to engage the work units beyond the rails. It will be noted that the lifter bars are discontinuous and do not extend under the bulk of the close spaced group of work units 32'. They do, however, extend beneath the widely spaced group of work units 32² and the widely spaced work unit 32³ and the last work unit 32⁴ of the close spaced group.

Between Figures 1 and 2, the elevator is raised, lifting the widely spaced work units 32², the widely spaced work unit 32³ and the last of the work units 32⁴ of the close spaced group, to an elevated position immediately forward of dogs 36 on an upper generally horizontally extending pusher bar 37. It will be noted in Figures 1 and 2 that an additional work unit 32⁵ is positioned in raised position rearward of the elevator and supported on a return conveyor 38.

Between the positions of Figures 2 and 3, the elevator remains in raised position, and the upper pusher bars 37 are moved forward, resulting in advancing the work units which are elevated. Thus as seen in Figure 3, the widely spaced work units 32² at the beginning are each advanced by one wide space and the last of the close spaced work units 32⁴ at the end of the path is likewise advanced by a wide space. The work unit 32³, which was formerly the last wide spaced work unit, was, however, not immediately contacted by a forward projection 40 on the top pusher bars, so that it was advanced a relatively shorter distance, being pushed off the elevator on to an opposite portion of the conveyor 38. At the same time the initial work unit 32⁵ supported on the conveyor 38 has been contacted by a forward pusher 41 on the upper pusher bar relatively late in the forward stroke, and advanced a shorter distance than that of other work units 32², to push it off the conveyor 38 on to the elevator 34.

At the same time that the upper pusher bar 37 is carried forward, the lower pusher bar 33 and its dogs are desirably retracted, each dog moving back one step to a position behind the next rearward work unit, and, in the case of the rearmost dog, to a corresponding blank position below the forwardmost wide spaced work unit 32², which is still on the elevator in elevated position.

Between the positions of Figures 3 and 4, the elevator moves down, carrying with it the work units supported thereon. Thus the work unit 32⁵ and the rearmost of the work units 32² now occupy the positions which the work units 32² occupied in Figure 1, while the forwardmost of

the work units 32² has joined the group 32' as shown in Figure 4. The work unit 32⁴ occupies the position of the work unit 32³ in Figure 1, while the work unit 32³ in Figure 4 remains in the upper position held by the return conveyor 38.

Between the positions of Figures 4 and 5, the lower pusher bars 33 and their dogs move forward, carrying the group of close spaced work units 32'; including the last member of the group, which is the forward formerly wide spaced work unit 32² previously deposited in front of the rearmost dog by the elevator. Nothing happens to the wide spaced work unit 32⁵, to the rearward of the work units 32², and to the forward work unit 32⁴ during this stroke. However, the conveyor 38 moves the work unit 32³ from the forwardmost position to the rearwardmost position, where it becomes the work unit 32⁵ as seen in Figure 1. The next cycle will then be carried out as indicated in Figure 1.

In the procedure described, it will be evident that widely spaced work units exist at the beginning and end of the sequence of work units, as shown in Figure 1, and that such widely spaced work units are advanced, adding one of the rearward widely spaced work units to the intermediate close spaced work units, and removing the forward close spaced work unit to make it a widely spaced work unit. Likewise the forwardmost work unit is deposited on a return conveyor and brought back to the extreme rearward position. It will be evident, therefore, that the invention provides a way of crowding intermediate work units of a sequence and spacing out initial and final work units, and where the work units are all moved through a single furnace space, this can to advantage be used to give more space for insertion of the first work unit and withdrawal of the last work unit, without requiring that the same wide space be maintained throughout the furnace.

Thus it will be evident that the tendency of the work units to swing and scrape the furnace wall or to strike against one another can be allowed for by wide spacing in the beginning and end of a given furnace, while intermediately furnace space can be economized, and heat losses minimized by relatively crowding the work units. It will also be evident that where several furnaces are in line, there may be several repetitions of the initial wide space, intermediate close space and final wide spacing illustrated in Figures 1 to 5. In such case, Figures 1 to 5 will represent only a portion of the total length and the various sections may suitably be identical, the pusher bar simply being extended as far as desired. Of course, where it is desirable to employ separate pusher bars for individual furnaces of the line, Figures 1 to 5 will represent a condition for an individual furnace of a group.

Where Figures 1 to 5 represent the condition for a line of furnaces, it will be evident that a wide spacing will frequently be employed to carry the work units over an obstruction, such as the end walls between one furnace and the next in the sequence or a partition in a furnace. Thus the obstruction could be located between two wide spaced furnace units, for example between the wide spaced units 32² in Figure 4. It will be noted that in order to move the rearward one of these units to the position of the forward one, they are always lifted and the forward motion takes place in raised position, so that no interference would occur with a wall of a furnace located below the rails 30. Another obstruction

can be located between the last close spaced work unit and the work unit 32⁴ of Figure 4.

In Figures 6 to 15 a structure is illustrated which carries out the steps generally described in reference to Figures 1 to 5. In this case the furnace line 31 consists of furnaces 31¹, 31² and 31³, preceded by an unloading and loading position 31⁴. The furnaces may be performing any suitable heating operation, but will preferably be electrically heated salt bath furnaces having electrodes 42 (Figure 8) and provided with side walls 43, end walls 44 and bottom walls 45, with interior working spaces 46 between. It will be evident that the furnaces may be suitably roofed if desired, in a manner not shown.

The number, temperature and sequence of the furnace will, of course, vary with the operation which is being performed, a suitable sequence being for example one of the following:

1. Carburizing followed by quenching.
2. Carburizing followed by an air dwell, followed by re-heat in a neutral bath, then martempering, then air cooling and finally a salt bath draw.
3. Austempering, consisting of a pre-heat, a high heat, a quench and a draw, accomplished in separate salt baths.
4. Annealing.
5. Cyclic annealing.
6. Drawing.
7. Brazing.

For example, the furnaces shown may consist of a preheat salt bath furnace 31¹, an austempering salt bath furnace 31² and a quenching salt bath furnace 31³.

The rails 30 extend continuously over the furnaces and are supported on structure 47 conveniently located at the sides, so that the space above the furnaces is kept clear for insertion, removal and translation of work units. The rails conveniently comprise opposite facing channels 48 and 50 (Figures 11 to 13), suitably joined by a strip 51 at the bottom, fastened as by welding. In effect a box section is produced. One of the upper flanges 52 shortened to leave a top slot 53, through which the dogs can extend. An angle 54 extends through the interior of each rail and acts as the pusher bar. The bottom flange 55 rests close against the bottom of the interior of the box section. Guiding rollers 56 are mounted along the pusher bars on studs 57 and serve to reduce the friction on sliding of the pusher bars with respect to the rails. At the appropriate intervals along the upstanding flanges 55' of the pusher bars are pivotally mounted dogs 58. The dogs, in their active position, have vertically extending pusher faces 60 (Figure 11) above the rails to engage the work units, but are capable of moving to an inoperative position by swinging about their pivots 61 during retraction, when the upper ends of the dogs engage and slide under the work units. The tendency to restore the dogs to their pushing position is due to the biasing on account of the fact that the greater part of the weight of each dog is below the pivot. The lower face 62 of each dog engages the lower flange 55 of the pusher bar in the active position of the dogs and acts as a stop. The dogs are adjusted for spacing by moving the pivot 61 along slots 63 in the pusher bars. It will be evident that if it is desired to obtain spacing out and crowding by the action of a single set of pusher bars, individual dogs may be more widely spaced than other dogs, as shown

in my copending application Serial No. 41,041 filed July 28, 1948 for Pusher Mechanism.

The adjustment of the pivot 61 in the slots is facilitated by providing pivot bolts for the pivots.

The pusher bars for each pair of rails, acting through the dogs conveniently contact the work units on the rails by engaging pusher pads 63' which are rigidly connected as by welding to header bars 64 of the work units 32. The header bars are suitably longer than the span of the rails so that they extend beyond the rails on each side for engagement by the elevator as later explained. The header bars of the work units are connected suitably intermediate their ends to hangers 65, on which the work 66 (Figure 8) is suitably held in the furnace space. It will be understood that the details of the fixtures by which the work is held on the work holders form no part of the present invention, although suitable fixtures are shown in my copending application above referred to.

The pusher bars are desirably connected at one end by a cross connection 67 and the operation of the pusher bars is accomplished by a suitable air cylinder 68 (Figure 15), having a piston not shown, whose piston rod 70 pivotally connects to a link 70' which pivotally connects to one end of a rocker 71, on a fixed pivot 72 between the ends of the rocker. The opposite end of the rocker pivotally connects to a link 73 which pivotally connects to the cross connection 67 of the pusher bars. The piston is constantly urged toward its retracted position by a source of fluid such as compressed air admitted through a pipe 74 and on the forward stroke is actuated by fluid at higher pressure admitted from the opposite end of the cylinder, for example compressed air supplied through a pipe 75 controlled by a valve 76, opened by the action of a solenoid 77, which is constantly urged toward the closed position of the valve by a spring not shown, and which operates to open the valve when energized.

The elevator 34 consists of a forward elevator unit 78 and a rearward elevator unit 80, spaced so as not to include the portion of the rails which carry the close spaced work units except the forwardmost as described in Figures 1 to 5. Each elevator unit has separate portions 81 and 82 located outside of the rails so as not to interfere therewith.

On each elevator on the side toward the rails is a lifting bar 35 which extends under the overhanging end of the header bar of the work unit at each point where it is desired to lift the work unit. The elevator units are suitably suspended from cables 83 wound on drums 84, the opposite cables at any position being cross connected by shafts 85. To assure uniformity of motion, the shafts 85 for each elevator unit are interconnected by chains 86 on sprockets 87. For uniformity of motion of the two elevator units, interconnection is provided by a chain 88 on sprockets 90, mounted on shafts 85 for two of the units. The shafts are carried by bearings 91 mounted on supporting structure 92 (Figure 7).

Drive of the elevator units through the shafts, sprockets and chains is accomplished by a reversible motor 93 having opposite windings 94 and 95 (Figure 15) and interconnected to one of the shafts 85 through a belt and pulley drive 94 (Figures 6 and 7). While the motor is shown as having two windings, it will be evident that as well known it may simply employ reversible connections.

In the upper position of the elevator it is im-

mediately below the upper pusher bars 37 and in the paths of their dogs. Whereas the dogs 58 on the lower pusher bars are upwardly directed, the dogs 36 on the upper pusher bars are downwardly directed. Furthermore, the dogs 36 are not required to pivot, since the work units are lowered out of the path of the dogs 36 during the retraction stroke of the upper pusher bars. The upper pusher bars 37 consist of forward portions 95, which are raised to clear interfering parts, slightly lower intermediate portions 96 guided and travelling on rollers 97, and rearward portions 98 also raised to clear interfering parts (Figure 9).

The upper pusher bars are cross connected at 100 at the forward end and at 101 at the rearward end. The dogs and other pusher abutments on the upper pusher bars are as described in Figures 1 to 5 inclusive. The rearward pusher abutment 41 as best seen in Figures 6 and 9 extends around in hook formation to clear interfering parts, and a similar construction is provided on the forward pusher abutment 40.

The upper pusher bars are only put through their forward stroke when the elevator is raised as shown in Figure 10, bringing the work units which are raised into position behind the dogs 36 for advance of the work units. As best seen in Figure 10, the upper pusher bars 37 at their intermediate portions 96 have T sections with the body downwardly directed, so that the flanges can be guided by the rollers 97. The lifter bars 35, on the elevator, support ends 102 of the header bars of the work units as the work units are pushed forward by the upper pusher bars.

The upper pusher bars are manipulated as shown in Figure 15 by a fluid cylinder 103, having a piston not shown, whose piston rod 104 is pivotally connected to a link 105, making pivotal connection to one end of a rocker 106, having a fixed pivot 107 intermediate its ends. The rocker at the opposite end pivotally connects to a link 108 which makes pivotal connection to the cross connection 109 of the upper pusher bars.

It is desirable to provide facilities for returning the last work unit to the position of the first work unit, and for this purpose a return conveyor 38 is employed as best seen in Figures 6, 7, 8 and 9.

The return conveyor suitably surrounds the furnace structure at the upper level, supported on the beams which hold the upper pusher bars and the elevator mechanism. A track 110 suitably guides and carries a chain 111 mounted at the corners on sprockets 112 (Figure 7) whose shafts are supported in suitable bearings. The sprocket at one corner is driven by a motor 113 through a reduction gear train 114 to turn the chain in any suitable direction. Carried on the track and operatively connected to the chain at positions 180° apart are hook carriers 115, having their hook ends directed toward the center of the structure. The hook ends extend into contact with the chain through an upper slot 116 in the track. Thus it will be seen that the last work unit 32³ when contacted by the pusher abutment 40 and supported on the elevator, is pushed off the elevator on to hook carrier at the end, and then carried bodily by driving the conveyor 38 to the position of the first work unit 32⁵ (Figure 1). At this position on a subsequent stroke of the upper pusher bars, it is pushed off the hook carrier by the forward pusher abutment 41 on to the elevator, so that when the elevator moves down it can reach the position for unloading and reloading of the work unit as indicated at 31⁴.

In the main embodiment shown, the elevator beams extend discontinuously along the lengths of the furnaces. In some cases, however, it may be desirable to have the beams extend continuously and simply omit the lifter bars where it is not desired to lift the work units. In Figure 14 continuous beams 117 of an elevator 34 are shown with lifter bars located only at spaced points. It may be desirable, however, to lift out all work units during a period of inactivity when the furnaces are merely to be held at temperature, or even to be cooled down, emptied, cleaned or to have the salt bath changed. For this purpose alternate lifter bars 35' are provided for insertion at points where lifter bars are not otherwise employed, so that all work units can be raised. Attachment is provided as by bolts extending through openings 118 cooperating with openings in the lifter bars 35'.

In operation of the device, it will be evident that the operator will discharge and charge the work on the first work unit in lower position. The subsequent manipulation will cause this first work unit to be lifted by the elevator, pushed forward by a pusher bar dog in upper position and then lowered into the first furnace 31'. In the particular illustration shown, only one of the work units will be employed in this furnace, but it will be understood that if several of the work units are used they will be advanced by the lower pusher bars to the last position in this furnace. The last work unit in the first furnace is then picked up by the elevator and raised to the upper position, at which it is again moved forward by the upper pusher bar a sufficient distance to bridge the walls between two furnaces. On the next lowering of the elevator, this work unit becomes the first work unit of the close spaced sequence in the second furnace 31². It is then moved forward through short steps by the lower pusher bars until it becomes the last work unit in this furnace. It will be understood, of course, that if it is desired to employ wide spacing in the beginning and end of this furnace, this may be done by the action of the lower pusher bars in accordance with the principles of my copending application, above referred to or by raising the work unit on the elevator and advancing it abnormally by the upper pusher bars at the appropriate points.

The last work unit in the second furnace is then lifted by the elevator, and in the upper position is pushed forward far enough to bridge the walls between the second and third furnaces. It is then lowered into the third furnace, where it will undergo further advance by the lower pusher bars.

The last work unit in the final furnace (only one such work unit is shown) is then raised by the elevator to a position where it will be contacted by the pusher abutments 40 on the upper pusher bars, and pushed forward off the elevator and on to the hook carrier of the return conveyor. The return conveyor is next operated through 180° to bring the last work unit to the upper position corresponding with the first work unit, at which the upper pusher bars on the next stroke push the work unit off the hook carrier and on to the elevator. When the elevator lowers, this work unit is then in position for loading and unloading to go through the cycle again. It will be understood, of course, that the unloading and reloading can be accomplished at separate stations if desired.

In some cases it is desirable to make the mechanism fully automatic, and a system of this char-

acter is indicated in Figure 15, to suggest the possibilities. A suitable source of electric current is provided through lines 120 and 121. A timer 122, conveniently of synchronous type, includes an armature 123, a field 124, a contactor 125, an internal disconnecting switch 126 and timer starting and holding relay 127, having a relay switch 128 and an electromagnet 130. Each time the return conveyor 38 moves through 180°, an abutment 131 carried by each of the hook carriers 115 momentarily closes a normally open switch 132 against the action of its compression spring 133. The switch 132 is connected in series with the relay winding 130 across the line. This energizes the relay, which is of the holding type (released when its circuit is independently broken), to close the circuit through the relay switch 128 in series with the normally closed internal switch 126 and the timer field across the line. The timer is thus started, and goes through a predetermined timer cycle, as well known, after which it closes its contactor 125 and holds the same closed for a predetermined time as well known and then momentarily opens its internal switch 126 in the well known manner. This breaks the circuit, causing the holding relay 128 to release, while at the same time the internal switch 126 again closes to its normal position in readiness for its next cycle.

The timer contactor 125 has in series therewith a limit switch 136 normally closed by a compression spring 137 and in series with a field winding 94 of the elevator motor to raise the elevator (suitable relays may be used if the current is too heavy for the timer contactor). Accordingly, as soon as the timer contacts 125 close, the elevator raises until an abutment 138 on the elevator opens the limit switch 136, at which time the elevator stops, and its automatic brakes set in accordance with well known practice. At the same time that the switch 136 is opened, an abutment 140 on the elevator closes a normally open switch 141, urged to open position by a compression spring 142. The switch 141 is in series across the line with a solenoid 143 which opens the pressure valve 144 of a fluid connection (suitably compressed air) 145 to move the piston in cylinder 103 on the forward stroke against a lower constant fluid pressure (preferably compressed air) applied to the retraction end of the cylinder through a connection 146 to retract the same. Therefore the upper pusher bars move forward.

As the upper pusher bars 137 approach the end of their stroke, the further travel is limited by the piston engaging against the end of the cylinder and the piston remains in that position until the forward stroke pressure on it is released. An abutment 147 on the upper pusher bars at the end of the stroke closes a switch 148 normally open, due to the action of a compression spring 150. The switch 148 is in series across the line with a normally closed switch 151 urged toward closing by a compression spring 152, and which is then in closed position, and with the reverse or downward moving field winding 95 of the elevator motor, so that as soon as the switch 148 closes, the elevator begins to move down, carrying with it the various work units in their advanced position. The elevator moves down until an abutment 153 thereon opens switch 151 and holds the same open, at which time the elevator motor stops and the automatic brakes set as well known. As the elevator moves down, the switch 141 is no longer closed by abutment

140, and opens, causing solenoid 143 to release, which releases the high pressure on the cylinder 103 and exhausts the same through valve 144. The constant pressure then retracts the upper pusher bars. When the elevator comes down, a support 154 thereon, carries a pivoted abutment 155 held in neutral position by springs 156 and 157, which engages and closes a position switch 158, which is in series across the line with the solenoid 77, which applies fluid pressure for the forward stroke on the lower pusher bars. The lower pusher bars 33 then move forward until an abutment 160 thereon encounters an operating lever 161 of the pivoted switch 158 and throws the switch 158 to open position, at which time the solenoid valve 76 opens and permits exhaust of the high pressure fluid through the valve, and the lower pusher bars 33 retract under the constant fluid pressure from the fluid connection 74.

When the top pusher retracts, its pivoted spring mounted abutment 162 moves past and closes position switch 163 in series with the return conveyor motor 113 with which it is in series, starting the return conveyor through its 180° of motion. As the conveyor approaches the end of its stroke an abutment 164 thereon moves past (transversely to the plane of the paper) and opens the switch 163, stopping the motion of the conveyor.

The conveyor also at the same time closes the switch 132 and starts the action of the timer for the next cycle.

It will be evident that the invention permits great flexibility in translating mechanism to suit the particular furnace process which is being employed. It will also be evident that the invention is very economical, and saves furnace cost, heat loss and salt consumption. The invention can also be applied to pit type and other furnaces which are not salt baths.

It will be evident that while the length of each step of motion at the upper level is likely in many installations to be greater than the length of each step at the lower level this is not necessarily the case, and the invention can be applied with any desired relation of steps at the upper and lower levels.

It will be evident that the invention is especially applicable to furnaces, but may also be applied to other devices, especially employing liquid baths, which are generally included herein.

In view of my invention and disclosure variations and modifications to meet individual whim or particular need will doubtless become evident to others skilled in the art, to obtain all or part of the benefits of my invention without copying the process and structure shown, and I, therefore, claim all such insofar as they fall within the reasonable spirit and scope of my claims.

Having thus described my invention what I claim as new and desire to secure by Letters Patent is:

1. In furnace mechanism, a furnace having a work space, rails along the top thereof, work units supported on the rails, pusher bars for advancing the work units along the rails, an elevator for raising the work units from the rails to an elevated position and for lowering the same, pusher bars in the elevated position for advancing the work units along the elevator, and means for correlating the operation so as to first raise the elevator carrying work units which are to be advanced at a given rate, then advance the work units at such rate in elevated position, then lower

the elevated work units, and independently advance the work units at a different rate by the pusher bars in a lower position.

2. In furnace mechanism, a furnace having a work space, rails extending along the top thereof and adapted to support work units, an elevator movable from a position opposite the rails to an elevated position, lifting bars on the elevator extending discontinuously and adapted to pick up the work units and supplemental lifting bars removably secured to the elevator to permit lifting intermediate work units during periods of inactivity in the furnace.

3. In furnace mechanism, furnace means having work spaces, rails extending along the top thereof and adapted to support work units extending into the work spaces, pusher bars at two different levels, one cooperating with the rails and one above the rails, means for advancing the pusher bars, and elevator mechanism outside the rails and including lifter bars adapted to engage the work units outside the rails and extending discontinuously along the rails so as to raise selected work units while leaving other selected work units unaffected by the elevator mechanism.

4. The process of translating work units in a pot-like furnace having a furnace space open at the top and maintaining spacing out of the units at the beginning and end of the furnace, which comprises suspending the work from above, raising the work units at the beginning of the sequence, advancing the raised work units at a relatively higher rate and thereby carrying them over the furnace wall, lowering the work units until they are suspended in the furnace, advancing the lowered work units at a relatively lower rate, raising the work units again after they have been advanced through the furnace space, and advancing the latter raised work units at a relatively higher rate and thereby carrying them over the furnace wall.

5. The process of transplanting work units from one pot-type furnace having a furnace space open at the top to another, which comprises suspending the work from above at one level in a first furnace, pushing the work units forward step by step as they are suspended in the first furnace, raising the work units to a higher level which clears the end wall of the first furnace, pushing the work units forward at the higher level and at a higher rate than that at which they advanced in the first furnace, lowering the work to the first level in a second furnace and there pushing the work forward at the first level.

6. In a furnace mechanism, a pot-type furnace having a furnace space open at the top and provided with an end wall, supports for work units near the top of the furnace space, work units on the supports depending therefrom into the furnace space and adapted to hold work below the supports in the furnace space, pusher mechanism for advancing the work units over the supports step by step at a particular rate, an elevator for raising the work units to a higher level above the end wall and for lowering the same beyond the end wall and pusher mechanism operating at the higher level for moving the work units when at the higher level step by step and at a different rate.

7. In a furnace mechanism, a plurality of pot type furnaces each having a furnace space open at the top and each having an end wall and arranged in line, supports at a lower level extending along the top of the furnaces, work units on the supports, depending into the furnace space and adapted to support work therein, elevator mechanism moving from a lower level to a higher level above the end wall and adapted to lift work units as they complete their cycle in one furnace and lower the same in the next furnace, and pusher mechanism for advancing the work units when raised by the elevator to the higher level, whereby the work units are carried across the intervening wall space between one furnace and the next and are lowered into the furnace space of the next furnace.

8. A pot type furnace having a furnace space open at the top and having an end wall, rails extending across the top of the furnace at a low level, the respective rails being at opposite sides of the furnace, work units having header bars extending across from rail to rail and outside the rails, the work units extending down into the furnace space of the furnace, pusher bars at the low levels for advancing the work units over the rails, an elevator engaging the header bars at either side beyond the rails and adapted to raise the work units over the end wall and lower the work units beyond the end wall by engaging the pusher bars and pusher bars at an upper level for advancing the work units when they are raised by the elevator.

9. In a furnace mechanism, a pot-type furnace having a furnace space open at the top, rails extending across the top at either side, work units riding on the rails, depending below the same into the furnace space and adapted to hold work in the furnace space, pusher bars at two different levels, one corresponding with the rails and one above the level thereof, acting on the work units, an elevator located outside the rails and engaging the work units, the elevator having discontinuous lifter bars which prevent the elevator from raising certain work units and auxiliary lifter bars mounted in the elevator at the points of discontinuity.
